UNITED STATES PATENT OFFICE

2,441,039

SPRING HEEL FOR FOOTWEAR

Herbert H. Smith and William Milk,
Bay Shore, N. Y.

Application November 8, 1946, Serial No. 708,524

1 Claim. (Cl. 36—38)

2

1 This invention relates to spring heels for foot-wear.

It is an object of the present invention to prevent and/or absorb the foot shock to an individual which may occur while walking, standing or working at an occupation that the individual may be engaged in.

It is another object of the present invention to provide a simple arrangement for the connection of a spring within a rubber heel wherein the spring arrangement will be confined within the heel as the heel is connected to the shoe.

It is another object of the present invention to provide an arrangement for connecting the spring within the heel to retain the same temporarily while the heel together with the spring arrangement is attached as a unit to the bottom of a shoe such that the connection can be made by merely rotating the retaining disc from the position where its projections have entered a slot for engagement or alignment with a groove so that the projections are within the groove to be retained thereby.

It is still another object of the present invention to provide a heel adapted to have a spring arrangement therein, whereby the spring arrangement can be easily removed from the heel and a spring arrangement of different tension and size can replace the original spring, whereby a shoe heel can be adapted for the use of persons of different sizes and weights.

According to the invention, there is provided in the rubber heel a recess adapted to receive the spring arrangement. The bottom of the recess forms the closure, is formed of material comprising the body of the heel and protrudes to some extent below the side edges of the heel. Within this recess, there is disposed the spring arrangement comprising two plates and a spring disposed therebetween. After the spring arrangement has been disposed in the recess, the plate on the upper face of the heel is secured by means provided upon the heel recess wall so as to retain the unit in temporary engagement with the heel. Any size spring arrangement can be fitted within the heel recess and if desired, the spring arrangement already in the heel can be readily removed and a new one replaced without a great deal of effort.

According to one form of the invention, projections are provided on the disc which are adapted to enter openings for aligning the projections of the disc with a groove in the side wall of the recess. The disc is thereafter slightly turned to confine the projections within the

groove. When it is desired to remove the spring arrangement, the disc can be turned back so that the projections can pass through the openings. The spring may be made of any thickness or width and is preferably made of tempered steel in order to give it the desired resiliency. The heel with the spring arrangement therein is thereafter placed upon the bottom of the shoe in the usual manner by means of shoe nails or brads or the like.

For further comprehension of the invention, and of the objects and advantages thereof, reference will be had to the following description and accompanying drawings, and to the appended claims in which the various novel features of the invention are more particularly set forth.

In the accompanying drawings forming a material part of this disclosure:

20 Fig. 1 is a bottom plan view of the heel having provisions for the insertion therewithin of the spring arrangement.

Fig. 2 is a cross sectional view taken on line 2—2 of Fig. 1, looking in the direction of the arrows thereof.

Fig. 3 is a transverse cross sectional view taken on line 3—3 of Fig. 1, looking in the direction of the arrows thereof.

Fig. 4 is a cross sectional view similar to Fig. 3 but showing the heel as it is attached to the bottom of the shoe by means of the usual shoe nails.

Fig. 5 is a top view of the heel having a spring arrangement therein wherein the arrangement is retained by a disc having projections thereon adapted to be registered within grooves in the side wall of the spring recess.

Fig. 6 is a cross sectional view taken on line 6—6 of Fig. 5 through the projections of the plate as they lie within the wall of the spring recess.

Fig. 7 is a similar view to Fig. 6, showing another modification of the invention.

Referring now to the figures, **10** represents a rubber heel having a recess **11** therein adapted to receive a spring arrangement. This rubber heel is made of rubber which has some resiliency but has less resiliency than the spring arrangement **12**. The bottom of the recess is formed from heel material **13** and this material protrudes downwardly from the forward part of the heel whereby to provide for a play of the material on the bottom of the heel so that the person may rest his weight upon the spring arrangement **12**. The spring arrangement **12** includes a spring **14**

and two plates 15 and 16. The plate 15 has bent up projections 17 to prevent the spring end from slipping laterally along the plate 15. The plate 16 is recessed at 18 to receive the opposite end of the spring and to likewise keep it from slipping laterally of the plate. The plate 16 has its periphery extended into a countersunk portion 19 of the recess 11 and against a shoulder 21. Cement material is placed on the side wall of the countersunk portion 19 to retain the spring 10 arrangement within the recess so that the heel and spring arrangement can be sold as a unit.

According to the modification shown in Figs. 5 and 6, cement is unnecessary to secure the plate 16 in place. In this instance, the plate is provided with a plurality of circumferentially spaced projections 22 adapted to pass through openings 23 so that the plate can be rotated to place the projections within groove formations 24. With the plate 16 thus formed and rotated, the spring arrangement will be retained within the recess 11.

The heel may now be sold as a unit and can be readily attached to leather members 27 on the bottom of a shoe 28 by means of shoe nails 29 in the usual manner that an ordinary leather heel is connected to a shoe bottom. When the unit has thus been connected to the bottom of the shoe, the spring arrangement will be positively and more securely retained within recess 11 so that even though the plate 16 becomes disengaged from the side walls of the recess, the spring arrangement will still be maintained within the recess as long as the heel remains in place upon the shoe.

In Fig. 7 the plate 16' is shown to be flat and its periphery is shown to be held in position by angular projection 30. In other respects this form of the invention is similar to the previous forms and like parts may be recognized by corresponding reference numerals.

The disc and the spring may be covered with soft pliable material such as cotton, felt or woolen fabric, or plastic. The spring may be made of any size and the wire can be either of round or flat sections.

While we have illustrated and described the

preferred embodiments of our invention, it is to be understood that we do not limit ourselves to the precise construction herein disclosed and the right is reserved to all changes and modifications coming within the scope of the invention as defined in the appended claim.

Having thus described our invention, what we claim as new and desire to secure by United States Letter Patent is:

A spring heel arrangement comprising a heel formed of resilient material, a recess within the heel having its bottom closed to provide at the bottom of the recess a body of resilient material adapted to be compressed inwardly within the recess as the shoe is worn and weight placed upon the shoe heel, a spring arrangement disposed within the recess and adapted to be compressed as the shoe is worn, means for securing the heel to a shoe bottom, said spring arrangement comprising two plates and a coil spring extended between the two plates, the plate in the open end of the recess being connected to the side wall of the recess whereby to temporarily retain the spring arrangement within the resilient heel material at least until the heel has been secured to the shoe, said plate adapted to extend over the open end of the recess having projections circumferentially spaced therearound and extending radially outwardly from the periphery thereof, said heel material about the recess having slots adapted to receive the projections of the plate, and groove formations adjacent the bottoms of the slots into which the projections of the plate can be rotated to thereby retain the plate within the heel recess.
